UNITED STATES PATENT OFFICE.

EARL A. EDWARDS, OF SHELLEY, IDAHO.

DESIGN FOR A BUCKET.

53,438.

Specification for Design. Patented June 17, 1919.

Application filed January 22, 1919. Serial No. 272,585. Term of patent 3½ years.

To all whom it may concern:

Be it known that I, EARL A. EDWARDS, a citizen of the United States, residing at Shelley, in the county of Bingham and State of Idaho, have invented a new, original, and ornamental Design for Buckets, of which the following is a specification, reference being had to the accompanying drawing, forming a part thereof.

The figure is a perspective view of a bucket, showing my new design.

I claim:

The ornamental design for a bucket, as shown.

EARL A. EDWARDS.
